UNITED STATES PATENT OFFICE

160,889

SET OF BRIDGE PLAYING GAME TABLETS

Arthur L. Redden, Vallejo, Calif.

Application April 11, 1949, Serial No. 1,894

Term of patent 14 years

(Cl. D34—5)

To all whom it may concern:

Be it known that I, Arthur L. Redden, a citizen of the United States of America, residing in the city of Vallejo, in the county of Solano and State of California, have invented a new, original, and ornamental design for a Set of Bridge Playing Game Tablets, of which the following is a specification; reference being had to the accompanying drawing, forming part thereof.

Fig. 1 is a plan view of the ace, king, queen, jack and ten spot tablets of the four suits in the set of bridge playing game tablets, showing my new design; and

Fig. 2 is a perspective view of one of the tablets. The two to nine spot tablets in each suit, not shown, have the same appearance as the ten spot of that suit, the denominator ten being replaced by the denominators two to nine inclusive. Each tablet has the same appearance in perspective as the tablet shown in Fig. 2, the respective denominator being substituted for "A." The backs of the tablets are plain or conventional.

The figures are shaded to indicate color contrast.

I claim:

The ornamental design for a set of bridge playing game tablets, as shown and described.

ARTHUR L. REDDEN.
